UNITED STATES PATENT OFFICE.

ELMER NICHOSON, OF LANSING, MICHIGAN.

VIBRATING ROLLER FOR PRINTING-PRESSES.

No. 853,109.

Specification of Letters Patent.

Patented May 7, 1907.

Application filed April 27, 1906. Serial No. 313,996.

To all whom it may concern:

Be it known that I, ELMER NICHOSON, a citizen of the United States, and a resident of Lansing, in the county of Ingham and State of Michigan, have invented a new and Improved Vibrating Roller for Printing-Presses, of which the following is a full, clear, and exact description.

The purpose of the invention is to provide a color vibrator for printing presses adapted for use in connection with distributing rollers where different colors are to be printed at one impression, and to provide a simple and effective device capable of being quickly and conveniently set up for adaptation to any desired number of colors, and to act in conjunction with distributing rollers of the ordinary type.

Another purpose of the invention is to render it possible to so adjust the color vibrating sections of the vibrating roller that adjacent colors will not be run one into the other, and so that the belts of colors may be of the same or of varying widths.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a plan view of a portion of a pony cylinder color press and the improved vibrator applied thereto; Fig. 2 is a longitudinal section through the improved vibrating roller; Fig. 3^a is a longitudinal section through a portion of the vibrating roller and a portion of the distributing roller, illustrating the initial or intermediate position of a distributing section of the vibrating roller relative to the form roller; Fig. 3^b is a view similar to that shown in Fig. 3^a, but illustrates the extent of the distributed surface when the distributing section of the vibrating roller is at the end of its stroke in one direction; and Fig. 3^c is a view similar to those shown in Figs. 3^a and 3^b, but illustrating the extent of the distributed surface when the distributing section of the vibrating roller has reached the limit of its stroke in the opposite direction; and Fig. 4 is an enlarged transverse section through the vibrating roller.

The vibrating roller A consists of a shaft 10 of suitable length, having a collar 11 near one end, and a fixed grooved wheel 12 or its equivalent at the adjacent extremity; and near the opposite end of the shaft 10 two closely related threaded surfaces 13 and 14 are produced, the inner one being of greater diameter than the outer one; and one of said surfaces has a left and the other one has a right-hand thread thereon, to receive lock and jam nuts 15 and 16; and in the further construction of the shaft 10 a key 17 is formed thereon, extending from the collar 11 to the outer threaded surface 13, as is illustrated in Fig. 2.

The shaft 10 carries series of cylindrical sections, said cylindrical sections 18 of one series being of a desired diameter, but the sections 19 of the other series are of a lesser diameter. The cylindrical sections 18 are the color distributing sections, and they, only, come in engagement with the form or distributing rollers A' in connection with which they operate, as is shown in Figs. 3^a, 3^b and 3^c. The distributing rollers A' may be of any desired type, and are provided with the customary shafts a.

The cylindrical sections 18 and 19 of the vibrating roller A are made in different lengths, so that any desired number of spaced color-distributing surfaces may be obtained, each of any desired length and spaced any desired or necessary distance apart, as may be called for in setting up the vibrating roller A for the different kinds of work.

Each cylindrical section 18 and 19 is provided with a bore 20, extending through from end to end, and a groove 21 in the wall of the bore, as shown in Fig. 4, so that while the cylindrical sections 18 and 19 may be readily slipped upon or removed from the shaft 10, they are prevented from turning on the shaft, and when the cylindrical sections are in position on the shaft they are locked end to end by the collar 11 and the nuts 15 and 16.

In Fig. 1 I have shown the adaptation of the improved vibrating roller to a pony press B to print four circular letters at one time in a multiple of colors, and four full page forms 22 are shown on the press locked in a chase 23 in the customary manner. The ink fountain 24 is of the ordinary type, each color 25 being laid for proper distribution to the appropriate type, and each color is backed or

held in place or separated in the usual manner by wadded tissue paper, or rags, for example. The vibrating roller A is set up so that the distributing sections 18 cover the type to which ink of the chosen color is to be applied, so as to insure the covering of said type as the sections pass back and forth, the spaces between the distributing sections 18 of the vibrating roller A being filled in by spacing sections 19 of proper length. The spacing of the distributing sections 18 is so calculated that in the operation of the vibrating roller A one color will not be rubbed into another, and such calculation will depend upon the extent of the throw of the said vibrating roller, it being the aim to so set the distributing sections 18 that they will distribute the colors on the form rollers A' within about an eighth of an inch of each other.

The operation of the color distributing sections 18 relative to the form roller A' is clearly shown in Figs. 3^a, 3^b and 3^c, wherein in Fig. 3^a the color 25 is just deposited upon the form roller, while in Fig. 3^b the color 25 is shown spread in one direction, and in Fig. 3^c as spread in an opposite direction, completing the width of the color belt. Further parts of the press shown in Fig. 1 consist of the ink roller 26 and its doctor 27 which delivers the ink to the vibrating roller A, the impression cylinder 28 and its fly 29.

The grooved wheel 12 of the vibrating roller A' is agitated in any approved manner, as for example by a fork 30 given a vibratory movement through a suitable connection with the driving mechanism of the press.

The improved vibrating roller is adaptable to any form of press, and may be used in running any desired number of colors. It saves time of the feeder, wear upon the machine, power and time to make ready, and

each sheet will have the inks applied the same distance apart whether the sheet is fed true or not.

Having thus described my invention, I claim as new, and desire to secure by Letters Patent,—

In printing presses, the combination with an ink fountain and removable wadded partitions therefor, dividing the fountain into a number of cells for different colors of ink, and a form roller operating in conjunction with the said fountain, of a vibrating inking roller adapted to take ink from said fountain, and consisting of a shaft, a series of removable and adjustable distributing sections and intermediate spacing sections located on said shaft, the spacing sections being of lesser diameter than the diameter of the distributing sections, said distributing sections corresponding in length, in number and arrangement to the length, number and arrangement of the cells in the ink fountain, the vibration of said inking roller and the relation of the distributing section thereof being such that the ink of one color received by the roller will be sharply defined from an adjoining color also received by the roller, one color being absolutely prevented from running into the other, a stop collar for the said section at one end of the shaft, and locking nuts for the sections at the opposite ends of the shaft, the sections being held by the locking devices named, in close end engagement one with the other.

In testimony whereof I have signed my name to this specification in the presence of two subscribing witnesses.

ELMER NICHOSON
